UNITED STATES PATENT OFFICE

ARTHUR B. BONNHEIM, OF CHICAGO, ILLINOIS

REFRIGERATING APPARATUS

Application filed April 18, 1927. Serial No. 184,530.

- My invention relates to what are commonly known as drink dispensing devices such as are used at soda fountains and other places where soft drinks are dispensed.
- 5 In drink dispensing devices for dispensing various forms of cold drinks, as heretofore constructed, it has been customary to cool the liquid thus held on draft by placing ice directly in the liquid. Certain forms of 55 these devices, on the other hand, have had the cooling accomplished by passing the liquid through a coil immersed in the cooling brine of a soda fountain and still further, in some cases, cooling has been attempted by 60 relying on the low temperatures of adjacent refrigerating devices. The type mostly used is where the ice is placed in the liquid. Certain disadvantages are inherent in this form of refrigeration. The melting ice thins the 65 beverage to a point where the taste and consistency are so greatly altered, that the beverage is spoiled and cannot any longer be sold. Beverage dispensers, moreover, dislike the handling of ice. Provisions must be 70 made to have it available, which is expensive, and which causes considerable annoyance due to the labor involved in caring for that which constantly melts. It is often so disagreeable to have chopped or loose ice about soda fountains, that there is a tendency today to install "iceless fountains", namely, a type employing a cooling brine mechanically circulated to produce the desired low temperatures.
- 75 25 With this tendency rapidly growing and the possibility of the absence of ice in the near future from soda fountains, I find that it is desirable to make some provision for cooling beverages on draft by means other than the insertion of ice directly into the beverage. Ice in contact with the beverage often causes too low a temperature, thereby separating the beverage. After business hours, the beverage is either allowed to go 80 uniced, or must be drawn off into a container which can fit into one of the compartments of the soda fountain or otherwise placed in a refrigerator.
- 85 One of the principal objects of the present invention is in the provision of a unitary 85 structure which may be used, preferably, in connection with a soda fountain or cabinet, having a cooling brine which can be circulated to cool the beverage without bringing the beverage in contact therewith. The beverage container is provided with a reentrant portion at its base which furnishes a cooling compartment into which a coil may be inserted for circulating the brine of the soda fountain, whereby to maintain the beverage 90 at a practically even temperature.
- 95 Another object of the invention is the provision of a motor driven pumping unit for automatically circulating the cooling brine through the coil, and so locating the coil that the beverage is never in direct contact therewith. Consequently, there is little possibility of the beverage being at different temperatures in the same container, nor is there 100 possibility of causing a portion of the beverage to freeze in order to keep the rest sufficiently cold.
- 105 Another advantage to be obtained by not passing the cooling coil through the wall of the container and into the liquid resides in 75 eliminating the problem of leaking joints. The joints at the coils are difficult to maintain due to vibration of the coils and the danger of fracturing the glass. On the other hand with the coil inserted into the liquid, 80 it is difficult to clean the interior of the container, inasmuch as the latter is permanently attached to the coil where it enters and hence cannot be removed. The beverage adheres to the coils, causing the formation of a coating 85 which is difficult to remove.
- 110 A still further advantage of this arrangement resides in eliminating the difficulty, which would arise, by tainting or otherwise rendering the beverage unfit by allowing it to 90 come into contact with the metal coil. Although certain metals could be used, which are noncorrosive, and which would not taint the beverage, yet such metals are expensive and are poor heat conductors and therefore 95 are not considered practical.
- 115 It is to be further remembered that my invention is a decided improvement over the type of drink dispensing apparatus, wherein the beverage is circulated through coils im- 100

mersed in the brine of the soda fountain or refrigerant container. In such cases, considerable difficulty has been experienced by the beverage freezing in the coils and pipes and the failure of the system to maintain a uniform temperature of the beverage while not in constant use.

Other objects and advantages of my invention will be apparent from the following detailed description when taken in connection with the accompanying drawings.

In order to apprise those skilled in the art how to construct and practice my invention, I shall now describe a preferred embodiment thereof in connection with the accompanying drawings, in which:

Figure 1 is a transverse vertical sectional view of a soda fountain, with a drink dispensing device embodying my invention associated therewith; and

Fig. 2 is an enlarged vertical sectional view of the drink dispensing apparatus.

As illustrated in the drawings, my invention is particularly adapted for use with soda fountains having a suitable cooling medium available, such as brine or a mixture of crushed ice and salt that may be circulated to cool the drink on draft. It will be understood, however, that the invention is not to be limited to the embodiment shown herein, inasmuch as it is possible to employ the drink dispensing device, constituting the invention disclosed herein, in connection with other refrigerators, or a cooling apparatus employed particularly for the drink dispensing apparatus.

In Fig. 1 I have illustrated a soda fountain 10 of any desired construction, having a cooling chamber 11, in which is disposed a mixture of crushed ice and salt 12. It was well known that this ice is constantly melting and thereby furnishes a sufficient cooling liquid that may be circulated through the intake pipe 13 leading to a drink dispensing device 15. This drink dispensing device may be located at any desired point, but I have illustrated it mounted on the counter 16 of the soda fountain 10. The piping installation of drink dispensing device 15 will be different in various cases due to the construction and arrangement of soda fountains. Intake pipe 13 may be passed through the counter 16 by means of the passage 17 and the cut-away portion 18' in the body of the fountain 10.

Drink dispensing device 15 comprises a base 16 of suitable shape having a seat 17 about the upper periphery thereof to receive a container 18. It is desirable to provide the interior of base 16 hollow to permit the installation of a motor driven pump 19 comprising a motor 20 and any suitable pump 21 connected to the motor by a flexible connection 22. Container 18 is preferably made of glass and is cylindrical in formation. Base 23 of

container 18 is provided with a reentrant portion 24 extending internally into the container a suitable distance. It will be observed that the reentrant portion 24 is integral, and therefore, provides a cooling chamber 25 which is liquid-tight with respect to the interior of container 18.

A cooling coil 27 extends upwardly into reentrant portion 24. Intake pipe 13 is connected at 28 to the pump 21 and the pump is connected to the coil 27 at 29. Return pipe 30 extends downwardly past the pump and through passage 17 and then around the cut-away portion 18' and into the cooling chamber 11, as illustrated in Fig. 1.

A cover 32 may be furnished for container 18, which permits an operable stirrer 33 to extend downwardly and into the container 18 for the purpose of allowing the liquid on draft to be suitably agitated at different intervals to prevent the heavier portions of the fluid from settling at the bottom.

It will be observed that the provision of the reentrant portion 24 eliminates the necessity of a fluid-tight joint at the points where coil 27 would otherwise enter the container. Those skilled in the art will appreciate the advantage to be obtained by this construction, because it eliminates the difficulty of maintaining a fluid-tight joint against the tendency of the vibration of motor 20 constantly to weaken and destroy the packing of the joint.

The device which I have shown herein is automatic in operation. To this end, I prefer to provide a thermostat 35 in circuit with the motor so that a constant low temperature will be provided by the cooling coil, this being accomplished by the motor periodically starting and stopping as the temperature rises and falls.

The ice water brine in cooling chamber 11 will be sucked upwardly through intake pipe 13 by means of the pump 21 where it will be forced through the cooling coil 27 and returned to the cooling chamber 11. Constant circulation will thus ensue and the liquid on draft will be maintained at an even low temperature. Maintaining the beverage at an even temperature also tends to preserve the beverage and permit it to be kept longer without the danger of spoiling. It also tends to preserve the mixture of the beverage and prevent the heavier portions settling to the bottom.

It will be further observed that the motor 20 and pump 21 are individually removable from their bases so that they may be readily repaired when necessary. The beverage is, of course, drawn off from the container 18 by means of faucet 37.

It is impossible accidentally to displace container 18 from base 16 in view of the recessed seat 17. On the other hand, coil 27 extends upwardly into the reentrant portion

- 24 which also tends to prevent any accidental displacement of container 18. This container is easily cleaned as it may be lifted upwardly over the coil 27 and taken to a sink where the interior may be thoroughly washed. This is one of the important advantages that the present disclosure obtains over a structure where the coil extends through the container into direct contact with the beverage. With the coil extending into the tank, it is impossible to remove the container from its mounting, because the liquid-tight joint at the entrance of the coil would naturally be destroyed. Moreover, it is exceedingly difficult to clean the interior where the coil is exposed to the beverage because the beverage tends to cling to and form a coating on the coil which is difficult to remove. On the other hand, direct contact of the coil in the beverage when the temperature of the liquid falls too low, causes the liquid to freeze on the coil and also reduces the temperature of the liquid to a point where the solids separate from the liquid.
- 25 The average metal in contact with the beverage will taint the latter and render it unfit for use. Certain metals might be used, however, which are noncorrosive but these metals are relatively costly and are poor heat conductors.
- 26 In view of the fact that the starting and stopping of the motor driven pump 19 is periodic and automatically controlled by thermostat 35, provision is made in the form of a visible indicator to indicate the operation of the motor through container 18. A light 40 carried by a socket 41 and secured to a bracket 42 is mounted on coil 27, preferably at the top in the dome 44 of reentrant portion 24. Failure of this light to illuminate periodically will indicate that the motor 20 or the pump has failed, or that the wiring is broken. In any event, the light will indicate failure of the device, which would otherwise not be noticed until the beverage loses its low temperature.
- 27 It will be understood that my invention is not to be limited to the use of mixed crushed ice and salt as a cooling medium, but may employ the brine of mechanical refrigerators, or any other cooling medium which may be available. On the other hand, I do not intend to be limited to a device having the motor and pump installed in the base, although this arrangement provides a unitary and compact structure.
- 28 Without further elaboration, the foregoing will so fully explain the gist of my invention, that others may, by applying current knowledge, readily adopt the same for use under varying conditions of service, without eliminating certain features, which may properly be said to constitute the essential items of novelty involved,
- 29 which items are intended to be defined and secured to me by the following claims.
- 30 I claim:
- 31 1. In a drink dispensing apparatus, the combination, in a unitary structure, of a cooling chamber having a suitable refrigerant therefor, a section located adjacent said cooling chamber for cooling liquids on draft comprising a container for the liquids, a coil in heat exchanging relation with but separate from said container, a connection between said coil and said cooling chamber, and means for circulating the refrigerant in said cooling chamber through said coil to cool the liquids on draft in said container. 70
- 32 2. In a drink dispensing apparatus, the combination in a unitary structure, of a cooling chamber having a suitable refrigerant therefor, a section for cooling liquids on draft comprising a container, a coil in heat exchanging relation with said container, means for separating the coil from the liquids to prevent contact with the liquids, and means for circulating the refrigerant for 85 said cooling chamber through said coil to cool the liquids on draft in said container.
- 33 3. In a drink dispensing apparatus, the combination, in a unitary structure, of a cooling chamber having a suitable refrigerant therefor, a section for cooling liquids on draft comprising a container, a cooling coil in heat exchanging relation with but separate from said container, and means for circulating the refrigerant of said cooling 100 chamber through said coil to cool the liquids on draft in said container.
- 34 4. In a drink dispensing apparatus, the combination, in a unitary structure, of a container for liquids on draft, a base for said container, and a cooling system concealed in said container and base for said liquids including a cooling coil in heat exchanging relation with said container and a motor driven pump for circulating a refrigerant through said coil. 105
- 35 5. In a drink dispensing apparatus, the combination, in a unitary structure, of a container for liquids on draft, a base for said container, a cooling coil in heat exchanging relation with but separate from said container, and a motor driven pumping unit in said base for circulating a refrigerant through said coil. 110
- 36 6. In a drink dispensing apparatus, the combination in a unitary structure, of a container for liquids on draft, a base provided with a seat for said container, said container having a reentrant portion constituting a cooling chamber for the liquids therein, a coil for said cooling chamber, said container being carried on said seat in removable relation with said coil, and refrigerant circulating means in said base for circulating a refrigerant through said coil. 115
- 37 7. In a drink dispensing apparatus, the 120

combination in a unitary structure, of a container for liquids on draft having an upstanding interiorly projecting extension at the lower end thereof to form an inner cooling chamber for the liquids in said container, said chamber being open at its lower end, and a cooling coil entering said chamber at said open end.

8. A drink dispensing apparatus comprising a container for liquids on draft having an interiorly projecting extension forming a cooling chamber which is open on one end, a coil for said chamber extending into said open end and a thermally controlled motor driven pump for circulating a refrigerant through said coil.

9. A drink dispensing apparatus comprising a unitary assembly having a base, a cooling coil, refrigerant circulating means connected to said coil, and a glass container including an integrally drawn reentrant portion providing a cooling chamber open at one end adapted for the reception of said cooling coil.

10. A container adapted to receive a beverage for cooling comprising a substantially cylindrical body provided with an inwardly extending, centrally positioned cooling chamber formed by proving an integral reentrant portion at one end of said body.

11. A drink dispensing apparatus comprising a container for liquid on draft, refrigerating means for cooling the liquid including a cooling coil and a motor driven pump for circulating a refrigerant through said coil, and a lamp in the motor circuit for indicating the operation of said motor driven pump.

In witness whereof, I have hereunto subscribed my name.

ARTHUR B. BONNHEIM.

combination in a unitary structure, of a container for liquids on draft having an upstanding interiorly projecting extension at the lower end thereof to form an inner cooling chamber for the liquids in said container, said chamber being open at its lower end, and a cooling coil entering said chamber at said open end.

8. A drink dispensing apparatus comprising a container for liquids on draft having an interiorly projecting extension forming a cooling chamber which is open on one end, a coil for said chamber extending into said open end and a thermally controlled motor driven pump for circulating a refrigerant through said coil.

9. A drink dispensing apparatus comprising a unitary assembly having a base, a cooling coil, refrigerant circulating means connected to said coil, and a glass container including an integrally drawn reentrant portion providing a cooling chamber open at one end adapted for the reception of said cooling coil.

10. A container adapted to receive a beverage for cooling comprising a substantially cylindrical body provided with an inwardly extending, centrally positioned cooling chamber formed by proving an integral reentrant portion at one end of said body.

11. A drink dispensing apparatus comprising a container for liquid on draft, refrigerating means for cooling the liquid including a cooling coil and a motor driven pump for circulating a refrigerant through said coil, and a lamp in the motor circuit for indicating the operation of said motor driven pump.

In witness whereof, I have hereunto subscribed my name.

ARTHUR B. BONNHEIM.
